ROBERT WALLACE, OF WALLINGFORD, CONNECTICUT.

Design No. 4,155, dated June 14, 1870.

DESIGN FOR SPOON-HANDLES.

The Schedule referred to in these Letters Patent and making part of the same

To all whom it may concern:

Be it known that I, ROBERT WALLACE, of Wallingford, in the county of New Haven and State of Connecticut, have invented a new Design for Spoon-Handle; and I do hereby declare the following, when taken in connection with the accompanying drawings and the letters of reference marked thereon, to be a full, clear, and exact description of the same, and which said drawings constitute part of this specification, and represents a view of the spoon.

This invention relates to a design for the handle of spoons, but is alike applicable to forks and similar articles of table-service, and consists in the peculiar configuration and ornamentation of the handle, as more fully hereafter described.

The handle is pointed, of Gothic shape, tipped with an ornament representing a strawberry branch, and, from about midway of the handle, at *a*, the edge of the handle is chamfered down to and dying out at the base, all as clearly shown in the accompanying drawings.

I claim as my invention—

The design for spoon-handle, as herein shown and described.

ROBERT WALLACE.
